[57] CLAIM

The ornamental design for a packaging container, as shown and described.

DESCRIPTION

FIG. 1 is a perspective view of a packaging container showing our new design; shown in partially open position; FIG. 2 is a front elevational view thereof;

FIG. 3 is a front elevational view thereof; shown in closed position; and,

FIG. 4 is a side elevational view thereof; the opposite side not shown is a mirror image thereof.

The rear is plain and unornamented.
